TYING MACHINE

Robert W. Smith, Darlington, Ind., assignor to Mid-States Steel & Wire Company, Crawfordsville, Ind., a corporation of Indiana

Filed May 6, 1963, Ser. No. 278,080
10 Claims. (Cl. 100—26)

This invention relates to tying machines and more particularly to a knotter for a wire tying machine.

Wire tying machines have heretofore been proposed in which a run of wire is threaded around a package and is drawn tightly around the package with the free end of the wire overlapping the initial run of wire. After the wire is drawn tight around the package the free end is twisted together with the initial run of wire and the initial run of wire is then cut off adjacent to the twist or knot. One of the problems of such machines has been the proper guiding of the wire during threading and releasing of the overlapping portions of the wire from the guiding means to be picked up and twisted together by the twister mechanism.

The present invention relates particularly to improvements in the twister head and guiding mechanism and has as its principal object the provision of means to guide the wire closely during threading thereof and to release or disengage the wire in response to movement of the twister head in a direction to pick up the wire for twisting.

Another object is to provide a tying machine in which the twister head operates through a cam during the initial portion of its movement from a rest position toward a twisting position to disengage the overlapping runs of wire from the guide member.

According to one feature of the invention, the guide member is formed with open topped grooves to receive and guide the wire during threading and is moved downwardly during initial movement of the twister head toward twisting position to release the wire. In another desirable construction, the bottoms of the wire guiding grooves are formed by vertically movable plungers which are moved upwardly by a cam during initial movement of the twister head to move the wires out of the grooves.

According to another feature of the invention, the guiding grooves are closed by a cover which is carried by the twister head to be moved away from the grooves during the initial movement of the head.

The above and other objects and features of the invention will be more readily apparent from the following description when read in connection with the accompanying drawings, in which:

FIG. 1 is a perspective view with parts broken away of a knotter mechanism for a tying machine embodying the invention;

FIG. 2 is a side view showing the parts in the threading position;

FIG. 3 is a view similar to FIG. 2 showing the parts in the knotting position; and

FIG. 4 is a partial view similar to FIG. 2 illustrating an alternative construction.

The tying machine, as shown, is generally similar to the machine more particularly described and claimed in the co-pending application of Flanigan and Smith, Serial No. 113,472, filed May 29, 1961, now Patent No. 3,157,109 issued November 17, 1964, except for changes in the knotter mechanism. The entire machine is therefore not shown herein, but it will be understood that it comprises a platform partially shown at 10 in FIG. 2 on which articles to be tied are received with a guide loop, not shown herein, extending above the platform to guide wire fed into the loop around the package to be tied. After the wire has been looped around the package, the feed

2

thereof is reversed to draw the wire tightly around the package after which the overlapping portions of the wire are twisted together and the wire is cut to complete a tying operation.

As shown in FIG. 1, the wire is guided in its passage across the platform by guide members 11 which lie at opposite ends of an elongated opening 12 in the platform and which communicate with the loop. Passage of the wire across the opening 11 is guided by a guide member comprising a block 13 formed with a pair of parallel grooves 14 in its upper surface. In using the machine, the end of the wire initially traverses the left-hand groove, as seen in FIGS. 1 and 2, and upon completion of the loop, the end of the wire is guided through the right-hand groove partially to overlap the initial run of wire. Upon completion of the loop the end of the wire is gripped by gripping means, as more particularly disclosed in the application referred to above, so that the wire is ready to be drawn tightly around the package and tied.

The guide member 13 is carried by a second block 15 which is supported for vertical sliding movement on a pair of vertical pins 16. Springs 17 urge the blocks 15 and 13 upwardly on the pins to the threading position illustrated in FIGS. 1 and 2.

The pins 16 are mounted on a carriage 18 which is slidable horizontally on a guide member 19. As shown, the carriage 18 includes a plate 21 resting on the guide member 19 and having side projections 22 which overlie the sides of the guide member 19. In this way, the carriage is free to move horizontally from a position in which the guide block 13 registers with the opening 12 to a position at the left side of the opening 12, as seen in FIG. 2. The carriage is urged toward the first mentioned or guiding position by a compression spring 23 acting between a fixed block 24 on the guide 19 and the carriage. A suitable stop is provided preferably by means of a rod around which the spring 23 is threaded to limit movement of the carriage to the right.

The overlapping portions of the wire are adapted to be twisted together for knotting by a twister head, indicated generally at 25, and which may be substantially identical to the twister head shown in the co-pending application referred to above. The twister head comprises a shaft 26 driven through universal joints 27 by a driving shaft 28 which turns first in one direction for twisting and then in the opposite direction for releasing the knot and cutting the wire. A pinion 29 is rotatably mounted on the shaft and is drivably connected through an intermediate pinion, not shown, to a twister pinion 31 which is formed with a slot in one side to receive the adjacent runs of wire, as indicated in FIG. 3. The pinion 29 is adapted to be drivably connected to the shaft 26 by a one-way clutch 32 so that upon rotation of the shaft in one direction the pinion will be driven and will drive the twister pinion 31 while upon rotation of the shaft 26 in the opposite direction the pinion 29 will be released therefrom.

The shaft 26 also carries a cam disc 33 having a cam pawl 33' thereon which is free to swing in one direction but whose movement in the opposite direction is limited by a stop pin 33''. When the disc 33 is turning in a clockwise direction to twist the wires together the pawl 33' will slide over the lever 34 freely but when the disc is turning counterclockwise the pawl will be held by stop pin 33'' and will engage and move the lever 34 which is pivoted on the twister head. The lever 34 engages a cutting knife 35 which is vertically slidable at one side of the head in registration with a slot 36 therein. When the cam disc 33 is turned in a counterclockwise direction, the knife blade will be urged upwardly to cut the initial run of wire adjacent to the twister head at the completion

of a twisting operation. Preferably a spring 37 is provided to urge the knife downwardly to the position shown in FIG. 2.

The twister head is slidably supported on the guide member 19 for horizontal movement from a rest position, as shown in FIGS. 1 and 2, in which the twister pinion lies at one side of the opening 12 to a twisting position in which the twister pinion is in registration with the opening 12 and receives the overlapping runs of wire to twist them together. As shown, the twister head is supported on guide blocks 38 which rest slidably on the guide member 19. For shifting the twister head, a fluid cylinder 39 is provided which is fixedly mounted and which has its piston connected to the twister head. Preferably the twister head and guide member are urged together by one or more tension springs 41.

During threading of the wire, the guide grooves 14 are covered so that the wire is completely confined therein. For this purpose, a cover plate 42 hinged at 43 on supporting brackets 44 is provided. The brackets 44 are secured to rods or posts 45 which are in turn secured to the twister head and project outwardly therefrom between the guide rods 16. With this construction, the cover plate 42 will move with the twister head so that as the twister head advances toward the twisting position, the cover plate will be moved away from the grooves 14 to allow the wires therein to escape.

For disengaging the runs of wire from the guide grooves 14 cam means are provided which are made effective during the initial movement of the twister head toward its twisting position. As shown in FIGS. 1 and 2, the cam means comprises a straight cam plate 46 having a straight outer end portion merging into a downwardly tapered cam surface adjacent to the twister head, as best seen in FIG. 2. The lower surface of the cam 46 engages a cam follower roller 47 carried by a yoke secured to the guide block 15. In the initial or rest position as shown in FIG. 2, the roller will engage the upper horizontal surface of the cam plate so that the guide block will be elevated. However, as the twister head moves toward the guide block during the initial part of the movement, the cam will move the guide block downwardly away from the wires therein to disengage the wires from the guiding grooves.

In operation of the mechanism as so far described, a wire is looped around a package to be tied, passing through the guide members 11 and the guide grooves 14 of the guide block 13. The free end of the wire is then clamped and the wire is drawn tightly around the package with the spaced parallel runs of wire still being retained in the grooves 14. With the wire in this condition, the motor 39 is energized to shift the twister head to the left, as seen in FIGS. 1 and 2, toward its twisting position.

During the initial part of this movement the twister head will move relative to the guide block due to the action of the springs 23 and 41. Therefore, the cam 46 will move the guide block downwardly to disengage it from the runs of wire and to leave them free. At the same time, the cover plate 42 will be moved away from the guide block. By the time the twister head comes into engagement with the guide block the parts will occupy the relative positions shown in FIG. 3 with the guide block being retracted and the cover plate being moved out of registration therewith.

Upon further movement of the twister head to the left, the guide block will be caused to move with the twister head against the spring 23. At the end of the movement of the twister head the runs of wire, as indicated at 48 in FIG. 3, will be moved into the slot in the twister pinion ready to be knotted.

At this time, the shaft 28 will be turned in one direction, clockwise, as seen in FIGS. 1 and 2, to drive the pinion 29 through the one-way clutch 32, thereby to turn the twister pinion 31 and twist the overlapping runs of the wire together. Upon completion of the twisting opera-

tion, shaft 28 will reverse to turn the cam disc 33 counterclockwise so that the pawl 33" will move the knife 35 upwardly sufficiently to cut off the initial run of wire adjacent to the twister head. The clutch 32 will release during this reverse turning so that the twister pinion 31 will align its slot with the slots 36 in the side members of the twister head to permit removal of the knotted wire therefrom. At this time, the motor 39 is energized in the reverse direction to move the twister head back toward its normal rest position. During this movement the twisted runs of wire will be pulled out of the twister pinion thereby releasing the tied package for removal. Also, the guide member will follow the twister head during its initial return movement until the guide member is stopped in its normal guiding position. Further movement of the twister head will move the cam plate 46 to the right relative to the guide member thereby allowing the guide blocks 13 and 15 to rise in response to the springs 17 to their initial position. At this time, the apparatus is ready for a subsequent tying operation.

FIG. 4 illustrates a modified construction, parts therein corresponding to identical parts in FIGS. 1 to 3 being indicated by the same reference numerals. In this construction, the guide member comprises a block 51 formed with a pair of vertically extending slots therein in which flat elongated plungers 52 are slideable. The plungers 52 normally occupy a raised position, as shown, so that they form with the top block 51 and with a shoulder 53 thereon parallel guiding grooves 54 corresponding to the grooves 14 of FIGS. 1 to 3. If desired, a spring may be provided urging the plungers upwardly to the position shown. The plungers are connected at their lower ends and carry cam follower rollers 55 which ride on a cam plate 56 secured to the twister head. The cam plate 56 is similar to the cam plate 46, and functions in the normal position shown in FIG. 4 to raise the plungers to their guiding position in which they define the guiding grooves 54. When the twister head 25 moves to the left relative to the guide member, the cam 56 will lower the plungers 52 until their upper ends are flush with the top of the block 51 so that the wires can slide freely over the top of the guide block and into the twister pinion as it moves toward them.

While two embodiments of the invention have been shown and described herein, it will be understood that they are illustrative only and not to be taken as a definition of the scope of the invention, reference being had for this purpose to the appended claims.

What is claimed is:

1. In a wire tying machine having a platform to receive an article to be tied and formed with an opening therein, a knotter mechanism comprising a knotter head slidably mounted beneath the platform, a twister pinion carried by the head and moved thereby from a first position at one side of the opening to a second position in registration with the opening, a guide member formed with guiding means to guide parallel runs of wire, means mounting the guide member for movement relative to the head and from a first position registering with the opening to a second position at one side thereof, means operated by initial movement of the head relative to the guide member from its first position toward its second position to disengage the guiding means from runs of wire engaged and guided thereby, the head after said initial movement engaging the guide member and moving it to its second position.

2. In a wire tying machine having a platform to receive an article to be tied and formed with an opening therein, a knotter mechanism comprising a knotter head slidably mounted beneath the platform, a twister pinion carried by the head and moved thereby from a first position at one side of the opening to a second position in registration with the opening, a guide member formed with guiding means to guide parallel runs of wire, means mounting the guide member for movement relative to

the head and from a first position registering with the opening to a second position at one side thereof, a cam member carried by the head and moved relative to the guide member by initial movement of the head from its first position toward its second position to disengage the guiding means from the runs of wire engaged and guided thereby, the head engaging the guide member after said initial movement to move the guide member from its first position to its second position.

3. The machine of claim 1 including a cover overlying the guide member to hold wire in the guiding means, and means mounting the cover on the head to move it away from the guiding means during said initial movement of the head.

4. The machine of claim 1 including a spring urging the guide member toward its first position, and a second spring connecting the head and guide member urging them into engagement with each other.

5. In a wire tying machine having a platform to receive an article to be tied and formed with an opening therein, a knotter mechanism comprising a head mounted for horizontal sliding beneath the platform, a twister pinion carried by the head, means to move the head from a first position at one side of the opening to a second position in registration with the opening, a guide member formed in its upper surface with a pair of wire guiding grooves, means mounting the guide member at one end of the head for vertical sliding movement and for limited horizontal movement relative to the head and for horizontal movement with the head from a first position registering with the opening to a second position at the other side of the opening, means operated by initial horizontal movement of the head relative to the guide member from its first toward its second position to disengage wire in the grooves therefrom, the head engaging the guide member after said initial movement and moving the guide member to its second position.

6. The machine of claim 5 in which the last named means is an elongated cam carried by the head and moved relative to the guide member during said initial movement.

7. In a wire tying machine having a platform to receive an article to be tied and formed with an opening therein, a knotter mechanism comprising a head mounted for horizontal sliding beneath the platform, a twister pinion carried by the head, means to move the head from a first position at one side of the opening to a second position in registration with the opening, a guide member formed in its upper surface with a pair of wire guiding grooves, means mounting the guide member adjacent to one end of the head for vertical sliding movement and for limited horizontal movement relative to the head and

for horizontal movement with the head from a first position registering with the opening to a second position at the other side of the opening, means supporting the guide member on the mounting means for vertical movement from a normal raised position adjacent to the platform to a lowered position spaced below the platform means operated by initial movement of the head relative to the guide member from its first position toward its second position to move the guide member downwardly from its normal raised position, the head engaging the guide member after said initial movement and moving it to its second position.

8. The machine of claim 7 in which the guide member is urged upwardly by a spring and the last named means is a cam carried by the head and engaging the guide member.

9. The machine of claim 5 including a cover normally overlying and closing the grooves in the guide member and connected to the head to be moved away from the grooves during said initial movement of the head.

10. In a wire tying machine having a platform to receive an article to be tied and formed with an opening therein, a knotter mechanism comprising a head mounted for horizontal sliding beneath the platform, a twister pinion carried by the head, means to move the head from a first position at one side of the opening to a second position in registration with the opening, a guide member formed in its upper surface with a pair of wire guiding grooves, means mounting the guide member at one end of the head for movement from a first position registering with the opening to a second position at the other side of the opening, vertically slidable plungers cooperating with the guide member to define the grooves, and means operated by initial movement of the head from its first position toward its second position to move the plungers in a direction to make their upper surfaces flush with the tops of the grooves thereby to disengage the wires from the grooves.
